**MULTIDISTRIBUTING DEVICE FOR DIE-SETTING
AND LINE-CASTING MACHINES**

Karl Debus, Bad Homburg vor der Höhe, Germany, assignor to Linotype G.m.b.H., Frankfurt am Main, Germany, a German company

Filed Nov. 14, 1960, Ser. No. 68,946

11 Claims. (Cl. 199—39)

This invention relates to matrix setting and line casting machines which have a multi-distributor mechanism which in known manner comprises a distributor, a plurality of receiving boxes and racks. Two fundamentally different constructions of matrix-setting and line-casting machines are known. The so-called single-distributor machine generally has a plurality of magazines from which setting is effected alternatively. The change-over from one magazine to another cannot be effected until all the matrices released before the magazine change-over have been distributed into the associated magazine. The magazine stacks are generally moved transversely into the magazine stack position between the carrier inlet and the distributor.

When large-body matrices are used on such matrix-setting and line-casting machines the standard-size magazines are frequently replaced by what are known as split magazines in order to save weight. The feed is effected in these conditions from the distributor through feed magazines. In this case, the split magazines are also moved transversely into their position between the carrier inlet and the feed magazine outlet. The feed magazines used in these conditions are usually disposed so as to be immovable.

Owing to the easy replaceability of the split magazines, the feed magazine can be swung together with the stack of split magazines in certain forms of construction. This swinging motion is independent of the movement of the split magazine stack and for this purpose a certain additional drive is provided.

By means of a multi-distributor mechanism in other known matrix-setting and line-casting machines a number of distributor mechanisms are permanently connected in each case to a corresponding number of magazines. This avoids the disadvantage that a change cannot be made to another magazine until all the previously released matrices have been distributed into the associated magazine. This permits mixing in multi-distributor machines.

Practical use of matrix-setting and line-casting machines has led to the demand for the capacity to set both ordinary type (small body) and large-body type, i.e. accommodate the maximum possible choice of different types in corresponding magazines in the machine. If, however, compliance with this requirement means sacrificing the advantages of the multi-distributor principle, it is necessary to provide a corresponding number of distributors owing to the larger number of magazines required. Up to a certain number of magazines, this is possible structurally but as the number increases it means an excessive structural outlay and costs which increase out of all proportion.

While obviating these difficulties the present invention combines the multi-distributor principle and the single-distributor system in a simple manner, preferably by constructing one or more of the magazines in a matrix-

2

setting and line-casting machine having a multi-distributor mechanism as a feed magazine to which one of a number of split magazines can be connected at any time after the style of the single-distributor mechanism. In this way it is possible for the first time to retain a limited number of distributors in a multi-distributor mechanism but provide a number of magazines in excess of that number. Instead of a magazine, a stack of magazines is connected to one or more of the distributors provided, in such manner that one of the magazines of the stack can be brought between the carrier inlet and the distributor at any time on the single-distributor principle.

Assuming, for example, that the matrix-setting and line-casting machine has four distributors and one of these distributors is in turn connected on the single-distributor principle to one of three magazines of a separate stack of magazines, then this magazine can be mixed with any of the three standard magazines, just as the three standard magazines can be mixed with one another.

20 The new distributor mechanism is preferably constructed in such manner that the distribution is effected through feed magazines into split magazines and the feed magazines are arranged to be rockable like the other standard magazines—which are always connected to the distributor—of the multi-distribution mechanism.

Together with the already known magazine suspension in multi-distributor machines, this gives a simple solution of the problem of feeding, into the split magazines, matrices which are to be distributed. Moreover, the invention has also very advantageously utilized the fact that the necessary stock of large-body matrices can be smaller than when ordinary-type matrices are used. For this reason, the large-body matrices are accommodated in the split magazines, and this has the further advantage of saving space and weight. The provision of a feed magazine also saves space insofar as concerns the set of magazines consisting of standard and split magazines, and also simplifies the change-over of the split magazines.

40 This adjustment of the split magazines to a position in front of the feed magazine is effected in simple manner by arranging the split magazines in a parallel relationship to one another and in their position to their associated feed magazine.

45 According to another embodiment of the invention, the split magazines are arranged radially to the pivot point of their associated feed magazine. This constitutes a particularly simple structural solution which, in addition, has the advantageous possibility of making a connection between the feed magazine and the adjusted split magazine so that even after the change-over to one of the standard magazines the still rotating matrices released from the split magazine before the change-over can be distributed into the associated split magazine independently of the change-over.

In one simplified embodiment of the invention the feed magazine is supported on the top standard magazine as long as matrices are released from a standard magazine. 60 When matrices are released from a split magazine the feed magazine bears on a stop. The constrained movement of the split magazines and standard magazines together with the raising and lowering of the entire stack of magazines is effected by connecting joints between the split magazines and one of the standard magazines. Ac-

cording to one modified embodiment, this joint-like support on one of the standard magazines may be replaced by supporting the bottom split magazine on the top standard magazine, for example by means of rollers.

According to a feature of the invention, the entire stack of magazines can be brought into the appropriate operative position by means of a drive in sequence with the position of the magazines, the above-described connection between the split magazine and the standard magazines by means of joints or direct support being utilized in order to bring the split magazines into position between the carrier inlet and the feed magazine.

The connection which is possible between the feed magazine and the adjusted split magazine when the split magazines are arranged radially to the pivot point of the associated feed magazine is not eliminated until a split magazine has again been moved into the collecting position, a damping system being provided for damping the lowering of the feed magazine in order to simplify the change-over from one of the standard magazines to one of the split magazines. For easy release and adjustability of this connection system, and for the purpose of operation effected together with the magazine change-over, the said connection may advantageously be effected electromagnetically according to the invention.

Embodiments of the present invention will now be described by way of example with reference to the accompanying drawings, in which:

FIGURE 1 is an elevation, partly in section, showing part of a matrix-setting and line-casting machine with four distributors, three standard magazines, a feed magazine and three split magazines disposed in parallel relationship to one another, the bottom split magazine having been brought into the matrix release position,

FIGURE 2 is an elevation similar to FIGURE 1, in which the top split magazine has been brought into the matrix release position,

FIGURE 3 is an elevation of a second embodiment in which the split magazines are arranged radially to the pivot point of the feed magazine, the bottom split magazine being supported on the top standard magazine by way of a connecting joint,

FIGURE 4 is an elevation similar to FIGURE 3, in which the bottom standard magazine has been brought into the matrix release position,

FIGURE 5 is a detail showing the bottom split magazine supported on the top standard magazine by means of rollers, the split magazines being arranged radially, and

FIGURE 6 shows an electromagnetically operated fixing system between the feed magazine and the top split magazine, the split magazines being arranged radially.

Like reference numbers indicate like parts in all the figures of the drawings.

A multi-distributor mechanism 10 (FIGURE 1) is rigidly fastened on a magazine supporting frame 12. The multi-distributor mechanism 10 comprises a distributor box (not shown), a distributor and a number of receiving boxes, the said number being determined by the number of magazine inlets. In the present example, the machine has four magazine inlets 14, 16, 18 and 20. The inlets are followed by four intermediate inlets 22, 24, 26 and 28. The intermediate inlet 22 adjoins a magazine 30, the intermediate inlet 24, a magazine 32, and the intermediate inlet 28, a magazine 34. The magazines, hereinafter referred to as the standard magazines, 30, 32 and 34, rest on magazine frames, the expression magazine in this context being used to denote in each case a magazine with the associated frame. The intermediate inlet 28 adjoins a feed magazine 36. While the standard magazines 30, 32 and 34 serve to receive the matrices the feed magazine 36 acts only as a bridge between the intermediate inlet 28 and the inlet to one of several split magazines. In the present examples three split magazines 38, 40, 42 are provided. FIGURE 1

shows the position in which the split magazine 38 is disposed in the matrix release position between a carrier inlet 44 and the feed magazine outlet 46.

FIGURE 1 shows the construction of the parallel split magazines. They are suspended at their sides by means of connecting links 48 and 50 which are aligned in parallel relationship to one another. The split magazines are mounted in the connecting links 50 by joints 52. The split magazine 42 is also mounted in the connecting link 48 by means of a joint 54. The split magazines 40 and 38 are so mounted that they have freedom for longitudinal movement relatively to the connecting link 48. For this reason pins 56 fastened rigidly on the split magazines 38 and 40 engage in slots 58 in the connecting link 48. The latter has its second fixed pivot point 60 on the standard magazine 34. The connecting link 50 has a bent arm 62 which extends as far as the pivot point 64. The latter is also the pivot point for the feed magazine 36. This mounting of the split magazines by means of connecting links 48 and 50 and a bent arm 62 is provided on both sides of the magazines.

The split magazines 38, 40 and 42 form a stack of magazines which is adjustable between the carrier inlet 44 and the feed magazine outlet 46 after the style of a parallelogram as a result of the mounting described, by means of the connecting links 48 and 50, 62. The adjustment is effected together with a swinging of the standard magazines about their pivots 66. A connecting link 68 interconnects the standard magazines 30, 32 and 34 and, during the swinging movement, effects a parallelogram motion. The movement of the standard magazines 30, 32 and 34 is coupled with the movement of the split magazines 38, 40 and 42 because both the connecting link 68 and the connecting link 48 are pivotally connected to the standard magazine 34.

In the position shown in FIGURE 1 the feed magazine 36 bears on a fixed stop 70 by means of a roller 72.

FIGURE 2 shows the position of the parallel-arranged split magazines 38, 40 and 42 when the top split magazine 42 is adjusted to between the carrier inlet 44 and the feed magazine outlet 46. On a lowering of the standard magazines 30, 32 and 34 the split magazines 38, 40 and 42 are also lowered in relation to the position shown in FIGURE 1, until the split magazine 42 is brought into the above-described position. The feed magazine 36 cannot follow this downward movement in comparison with the position shown in FIGURE 1, since it bears on its stop 70 in the manner described. The stop 70 forms a fixed abutment rigidly connected to the magazine supporting frame 12.

FIGURES 3 to 6 show the arrangement of the split magazines 38, 40 and 42 in a modified embodiment. A considerable difference from the embodiment shown in FIGURES 1 and 2 is that the split magazines 38, 40 and 42 in any possible position are aligned radially to the pivot point 64 at the top of the feed magazine 36. This alignment is produced by an arm 74, which is mounted in the pivot point 64. At the opposite end a connecting link 76 is rigidly connected to the arm 74. This connecting link 76 is in turn pivotally connected to the split magazines 38, 40 and 42 by means of fastenings 78. A second connecting link 80 is rigidly connected to the arm 74 in a similar manner and carries the split magazines 38, 40 and 42 at its other end by means of fastenings 82.

A connecting link 84 is mounted on the bottom split magazine 38 and the top standard magazine 34 by pivots 86. The split magazines 38, 40 and 42 form a stack of magazines which is pivotable by means of the connecting links 76 and 80 and their common arms 74 radially to the pivot point 64 thereof. The individual split magazines 38, 40 or 42 are adjusted by pivoting about this pivot point 64 between the carrier inlet 44 and the feed magazine outlet 46. The adjustment is effected together with a pivoting of the standard magazines about their pivot points 66. The movement of the standard maga-

zines 30, 32 and 34 is coupled with the movement of the split magazines 38, 40 and 42 because both the connecting link 68 and the connecting link 84 are pivotally connected on the standard magazine 34.

In the position shown in FIGURE 3, the feed magazine 36 bears, by a roller 72, on the stop 70.

FIGURE 4 shows the position of the radially arranged split magazines 38, 40 and 42 when the bottom standard magazine 30 has been adjusted between the carrier inlet 44 and the intermediate inlet 22. On lifting the standard magazines 30, 32 and 34, the split magazines 38, 40 and 42 are also lifted in relation to the position shown in FIGURE 3 until the feed magazine 36 is lifted from the stop 70 by the contact of its roller 72 on a slide element 88. On the further lifting, both the split magazine stack and the feed magazine 36 together with the standard magazine stack are lifted into the position shown in FIGURE 4.

Instead of the connecting link 84, a support 90, as shown in FIGURE 5, may be provided to connect the standard magazine stack and the split magazine stack. A roller 92 rolls on the support 90, which is mounted on the top standard magazine 34, and the roller 92 is in turn mounted on the bottom split magazine 38.

The arrangements described thus far enable a change-over to be made from any one of the standard magazines to a given split magazine irrespective of whether the matrices previously released from the standard magazine have already been re-distributed to said standard magazine. An operation in the reverse direction, that is to say a change-over from one of the split magazines to a normal magazine, presupposes with one exception that the matrices previously released from the split magazine are re-distributed into the said split magazine before the actual change-over takes place. The exception is the change-over from the bottom split magazine to one of the standard magazines. During this operation, the split magazine 38 and the feed magazine 36 are lifted simultaneously, that is to say the matrices released before the change-over process can be distributed into the split magazine 38 by way of the feed magazine 36 independently of the operation of the complete stack of magazines.

In a further embodiment of the invention it is possible to change over without any restriction from any one of the split magazines to a standard magazine, it being unnecessary to await the distribution of the previously released matrices. As shown in FIGURE 6 this possibility is provided by an arrangement which provides a connection between the feed magazine 36 and one of the adjusted split magazines 40 or 42. In FIGURE 6 the connection is shown between the feed magazine 36 and the top split magazine 42. This connection device is situated directly at the outlet 46 of the feed magazine 36 and the adjacent inlet of the split magazine 42. The feed magazine carries locking hooks 94 which are adapted to swing out on both sides and which can each engage in opposite notched plates 96 disposed on both sides of the split magazines 40 and 42. No connection is provided between the feed magazine 36 and the split magazine 38 since the two magazines lie in one plane in relation to one another by the joint-like or roller-like support on the top standard magazine, both in the collecting position and during any operation out of this position. The swinging movement of the locking hooks 94 is advantageously effected electromagnetically by means of a solenoid 98.

To simplify the operating process a damping system is provided for damping the lowering movement of the feed magazine 36 and comprises a piston 102 and a cylinder 100 mounted pivotally on the supporting frame 12. The piston rod 104 is, in turn, pivotally mounted on the feed magazine 36.

The damping system comes into operation when a change-over is made from one of the standard magazines to one of the split magazines. For example, assume that

a change is made from the operating position shown in FIGURE 4 to a matrix release from one of the split magazines 38 and 40, the fixing system shown in FIGURE 6 being provided between the feed magazine 36 and the top split magazine 42. The change-over is then followed by the release of the connection system by electromagnetically-operated disengagement of the locking hooks 94. The feed magazine 36 thus drops under its own weight until it bears by its roller 72 on the stop 70. The piston 102 in the cylinder 100 is moved down by means of the piston rod 104 and thus the lowering movement of the feed magazine 36 is damped. At the same time, the standard and split magazines move in opposition to this movement of the feed magazine 36 until the required split magazine is brought between the carrier inlet 44 and the feed magazine outlet 46 in the matrix release position.

It will be appreciated that more than one feed magazine and associated split magazines may be provided if desired.

I claim:

1. A matrix-setting and line-casting machine comprising in combination a multi-distributing mechanism, a plurality of standard magazines positioned in operative relation to and extending downwardly from said multi-distributing mechanism, a feed magazine of a shorter length than said standard magazines positioned in operative relation to and extending downwardly from said multi-distributing system, a plurality of split magazines, means mounting said split magazines in operative relation to said feed magazine and said standard magazines, and carrier means positioned at the lower ends of said standard magazines and said split magazines.

2. The combination according to claim 1 which is further characterized by said standard and split magazines being arranged one behind the other from the front to the rear of said machine with said magazines being inclined steeply with respect to the horizontal.

3. The combination according to claim 2 including means pivotally mounting the split and standard magazines for movement to bring any one of them into operative relationship with the carrier means.

4. The combination according to claim 3, including means mounting the split magazines parallel to one another and to the associated feed magazine movable with respect to said feed magazine for selectively positioning one of said split magazines in line with said carrier means and said feed magazine, said mounting means including a parallel motion linkage.

5. The combination according to claim 3, including means mounting the split magazines extending radially of the pivotal axis of the associated feed magazine by a member pivoted about that axis for selective movement into an in-line position of a selected one of said split magazines with said feed magazine and said carrier means.

6. The combination according to claim 3, wherein the feed magazine is supported by an adjacent standard magazine to move therewith so long as any standard magazine is in operative relationship to the carrier outlet, and wherein a stop is provided to engage the feed magazine and hold it stationary when any split magazine is moved into operative relationship to the carrier outlet.

7. The combination according to claim 6, wherein the split magazines and the standard magazines are arranged to pivot together to bring any one of them into the operative relationship to the carrier outlet.

8. The combination according to claim 7, wherein the standard magazines are inter-connected by links and the split magazines are inter-connected by links and to one of the standard magazines to constrain them for movement together.

9. The combination according to claim 7, wherein the standard magazines are inter-connected to pivot together and the split magazines are inter-connected to pivot to-

gether and are mounted above the standard magazines with the lowest split magazine supported on the top standard magazine.

10. The combination according to claim 5, further including a device for connecting the feed magazine to a split magazine with which it is aligned which connection is maintained when the magazines are moved to bring any standard magazine into operative relationship with the carrier outlet but is broken when the magazines are subsequently moved to bring a split magazine into opera-

5 10 15 20 25 30 35 40 45 50 55 60 65 70 75 80 85 90 95 100

tive relationship to the carrier outlet, and a damping device for damping movement of the feed magazine.

11. The combination according to claim 10 comprising electromagnetic means for actuating the connection device.
